UNITED STATES PATENT OFFICE.

CHARLES B. ABBOTT AND SAMUEL ABBOTT, OF CLEVELAND, OHIO, ASSIGNORS TO THE ABBOTT ELECTRIC AND MANUFACTURING COMPANY, OF SAME PLACE.

CIGAR-LIGHTER.

SPECIFICATION forming part of Letters Patent No. 644,658, dated March 6, 1900.

Application filed January 27, 1899. Serial No. 703,563. (No model.)

To all whom it may concern:

Be it known that we, CHARLES B. ABBOTT and SAMUEL ABBOTT, citizens of the United States, and residents of Cleveland, county of 5 Cuyahoga, and State of Ohio, have invented a new and useful Improvement in Cigar-Lighters, of which the following is a specification, the principle of the invention being herein explained and the best mode in which we have 10 contemplated applying that principle, so as to distinguish it from other inventions.

The annexed drawings and the following description set forth in detail certain mechanism embodying the invention, such disclosed 15 means constituting but one of various mechanical forms in which the principle of the invention may be used.

In said annexed drawings, Figure 1 represents a plan view of our improved lighter, the 20 case being shown in horizontal section. Fig. 2 represents one side elevation of the mechanism of the lighter, showing a part of the cover of the case in section. Fig. 3 represents the other side elevation of the machine 25 with the case removed. Fig. 4 represents a partial side elevation with portions of the mechanism removed. Fig. 5 represents a view similar to that shown in Fig. 4, but showing the mechanism in a changed position; and 30 Fig. 6 represents a detail view.

A dynamo-electric machine A is secured to a suitable base. Upon one end of the armature-shaft is secured a pinion a, Fig. 2, which meshes with a segmental gear B, mounted 35 upon the end of a rod a', secured to suitable stationary supports. Said segmental gear is provided with a stop-lug b, which overlaps the magnets of the dynamo-electric machine, as shown in Fig. 1, and which limits the down- 40 ward movement of the segment, a soft-rubber buffer being interposed between the lug and the metal of the magnet to receive the impact. To a laterally-projecting lug b' is secured one end of a spring C, the other end of 45 the latter being secured to the upper end of a post D', which is secured to the base of the lighter. A catch b² is pivoted upon and hangs vertically from an extension b³, formed upon the segment, as shown in Fig. 2.

One end of a lever D is fulcrumed upon the post D', Fig. 2, and is provided with a pin d,

secured thereto, Fig. 1, which engages a recess b⁴ on the catch b², said catch being formed with a cam-face b⁵ below said recess, engagement of the pin and catch being effected by a 55 spring b⁶, the ends of which are secured to said catch and lug b', respectively.

Near the free end of lever D is attached one end of a link e, the other end of which is attached to the end of an arm E, secured to a rock-shaft E', journaled in bearings secured to the under side of the top of the case and actuated by a spring e' to normally maintain a horizontal position of said arm E, as shown in Fig. 2. Secured to said lever D at two points 60 65 between its ends are two inwardly-extending arms D² and D³.

Secured to the base of the machine and below the free end of the lever D is a grip D⁴, and a guide D⁵ for guiding said lever in its 70 movement is also similarly secured.

An angle D⁶, interposing a rigid edge d' in the path of the cam-face b⁵, is secured below the catch b², Figs. 1 and 2, a soft-rubber buffer being secured to the upper face of said 75 angle to receive the impact of lever D.

Fulcrumed upon the upper end of a support F is a lever G, upon the outer end of which is secured an extinguisher G', which when lowered rests upon a torch which is supported in a seat H', formed by two prongs h at the end of an arm H, secured to said support F below and parallel with lever G. The inner end of said lever G projects into the path of the arm D³ and has projecting from 85 it laterally a pin g.

A catch-lever J, formed with a laterally-projecting lug j, is pivoted upon the support F, said lug engaging a depression h', formed upon the lower edge of a reciprocating bar 90 H², seated in the arm H, as shown in Fig. 4, such engagement occurring when the extinguisher-lever is in its normal lowered position, as shown in Fig. 3. A small spring j' is secured at one end to the lug j and at its 95 opposite end to the support F and tends to throw the catch-lever J toward the right of the machine, as represented in Fig. 3. A second spring h² is secured at one end to the bar H² and at its opposite end to said support 100 F and tends to throw the bar toward the right, as in the case of the catch-lever. The

right-hand end of the said bar projects some distance into the torch-seat H' , as shown in Fig. 4, resting against the upper portion k of the torch K when the latter is seated, as shown.

5 A releasing-lever M is pivoted upon the support F in Fig. 4, its right-hand end m , as viewed in said figure, projecting through an aperture f some distance beyond the opposite side of said support, as shown in Fig. 1, said 10 end lying in the path of the arm D^2 . The left-hand end, Fig. 4, of said lever M rests against a downwardly-projecting lug h^3 of the bar H^2 , said lever being so weighted that said end is constantly urged in an upward direction.

15 The torch K is provided with a contracted neck k , whereby it may be removed from its seat by lifting and said neck passed out from between the ends of the prongs of the torch-20 seat. Upon the end of the armature-shaft opposite that upon which is secured the pinion a is secured a pinion a^2 , Fig. 3, connected with a pinion a^3 through an intermediate gear a^4 . One end of a reciprocatory and oscillatory arm N is journaled upon a wrist-pin a^5 , secured to pinion a^3 . Said arm is supported at an intermediate point upon a stud o , secured to an upright support O . Said arm is bent, as shown in Fig. 1, its free end n 25 projecting to within a short distance of the wick-tube of the torch, as shown in Fig. 6. Upon said end is pivoted or hinged a hood N' , actuated downwardly by a spring n' , secured to and its downward movement being limited 30 by contact with said arm N . Said hood forms a support for a coiled spring n^2 , secured therein at one end, the free end of said spring projecting a short distance from the hood, as shown in Fig. 6. The hood itself projects a 35 short distance through a slot g' , cutting the lower edge of the extinguisher, and is provided with an inclined front face n^3 . The arm N is made in two metallic sections N^2 and N^3 , separated from each other by some distance and 40 connected by a strip of insulating material N^4 , Fig. 1. A wire conductor w is connected with one terminal of the dynamo and with the arm-section N^2 . A second wire conductor w' is connected with the other dynamo-terminal and 45 with the support F . Support O is insulated from support F in any suitable manner. An electrical circuit is thus formed in which the wick-tube of the torch and the end of the spring n^2 form terminals, with a spark-gap 50 between them.

55 The operation of the device is as follows: The end of the operating-lever D and the grip D^4 are grasped and the lever pressed downwardly into the position shown in dotted lines, 60 Fig. 2, thereby causing the arm N to reciprocate and oscillate, contacting the terminals of the circuit and generating a current in the latter, whereby a spark is formed in the vicinity of the wick across the gap and ignites 65 the wick of the torch. The pivoted catch b^2 being drawn down with said lever D is released from its engagement with the pin d by

the action of the cam-face against the angle edge d' , whereupon the spring C draws the segment rapidly back, rotating the armature 70 in the opposite direction, again contacting the terminals, and forming another spark, as before, which may light the wick in case the spark produced during the downward movement of the operating-lever does not accomplish the lighting. On releasing the operating-lever it is drawn back to its initial position by the spring-actuated lever E . The operating-lever thus forms a positive means for rotating the armature in one direction, and 80 the spring forms a second rotating means for rotating the armature in the opposite direction on the disconnection of the lever from the segmental gear. During such operation the arm D^2 is carried downwardly with the 85 operating-lever D and engages the projecting end portion m of the releasing-lever M , raises the opposite end of the latter against the end of the bar H^2 , whereby the latter is raised and releases the lug j of the catch-lever J 90 from the depression h and permits the spring j' to draw said lever into the position shown in dotted lines in Fig. 4. In such position said lever may be engaged by the pin g of the extinguisher-lever G , as also shown in dotted lines 95 in said figure. Such engagement is effected on the downward stroke of the operating-lever by the engagement of the arm D^3 with the rear end of the extinguisher-lever, the latter thus being locked in a raised position, as shown in 100 Fig. 5. The lighted torch is then removed from its seat, whereupon the bar H^2 is actuated by spring h^2 to project farther into the seat-space, as shown in Fig. 5, and reengages the lug j on the catch-lever. The torch now 105 being replaced pushes the bar back into its normal position, (shown in full lines in Fig. 4,) and thus causes the catch-lever to release the extinguisher-lever, thereby permitting the latter to drop and the extinguisher to extinguish the flame of the torch. As a result 110 of the combined reciprocatory and oscillatory movements of the arm the terminal connected therewith is given a rotary movement first in one and then in the opposite direction, contacting the torch wick-tube during each of 115 these rotations. In rotating so as to make contact on its downward movement said terminal is required to have the necessary amount of rigidity not to catch and hold on 120 the edge of the wick-tube, while during the rotation in the opposite direction, in which contact is made on the upward movement, the same amount of rigidity is not required. This difference of rigidity is imparted to the 125 said terminal by the spring-actuated hood illustrated. In the upward contacting movement, in which the lesser rigidity is required, the degree of flexibility of the coil determines the degree of flexibility of the terminal, which 130 is hence very small. On the downward contacting movement the coil strikes the upper portion of the hood and the latter is lifted against the action of the less-flexible spring

n'. Hence the latter spring determines the degree of flexibility of said terminal during such movement. The terminal is hence flexible in both directions and the proper degree of flexibility is attained in each. Such construction insures an indefinite length of life to such terminal. By mounting said terminal in the hinged hood or support liability to damage to said terminal in its downward movement caused by tilting the torch toward the latter and thereupon pressing the lever is reduced to a minimum. In such case the inclined face *n'* engages the edge of the wick-tube on such downward movement, and being thereupon raised on its hinge slides off, whereupon the hood is released from engagement with said tube without damage to the wire-terminal.

Other modes of applying the principle of my invention may be employed instead of the one explained, change being made as regards the mechanism herein disclosed, provided the means covered by any one of the following claims be employed.

25 We therefore particularly point out and distinctly claim as our invention—

1. The combination of an electric circuit, two terminals in said circuit relatively retractile, a removable torch, an extinguisher, 30 said terminals adapted to ignite said torch, means for operating said extinguisher to extinguish the torch and controlled by the latter, substantially as set forth.

2. The combination of a magneto-electric machine and an electric circuit, a pivoted lever one end of which is provided with a flexible terminal and the opposite end of which is journaled on a pin revolved by the armature-rotating means of the magneto-electric machine, a lamp in said circuit having its wick-tube in the vicinity of and capable of being contacted by said terminal, substantially as set forth.

3. The combination of a magneto-electric machine and an electric circuit, mechanism for rotating the armature of said machine, a lever in said circuit, and having one end provided with an electric terminal, a lamp in said circuit whose wick-tube forms a second terminal in said circuit, said armature-rotating mechanism adapted to contact said two terminals, an extinguisher, means connected with said armature-rotating mechanism for raising said extinguisher, means for locking the latter in such raised position, and means operated by said lamp to release said extinguisher, substantially as set forth.

4. The combination of a torch-seat, a torch removable from said seat, an extinguisher, means for raising the latter from the torch, 60 means for locking same in such raised position, and means for unlocking same actuated by said torch in seating, substantially as set forth.

5. The combination of a torch-seat, a torch removable from said seat, an extinguisher, means for raising the latter from the torch, means for locking same in such raised position, and a bar projecting into the torch-seat for unlocking the extinguisher, substantially 70 as set forth.

6. The combination of a torch-seat, a torch removable from said seat, an extinguisher, means for raising the latter from the torch, 75 means for locking same in such raised position, and a bar projecting into the torch-seat for unlocking the extinguisher, said bar actuated by said torch in seating, substantially as set forth.

7. The combination of a torch-seat, a torch removable from said seat, an extinguisher, means for raising the latter from the torch, 80 means for locking same in such raised position, and a bar projecting into the torch-seat for unlocking the extinguisher, said torch 85 provided with an inclined portion for engaging the end of said bar to effect such unlocking, substantially as set forth.

8. The combination of a torch-seat, a torch removable from said seat, an extinguisher secured to a lever pivoted in the vicinity of said seat, means for actuating said extinguisher-lever to assume a raised position, a catch-lever for locking said lever in such position, a bar disconnectably engaging said catch-lever, 90 said extinguisher-lever-actuating means adapted to disconnect said bar and catch-lever, means for urging said bar against the seated torch and operative during the disconnection of said bar and catch-lever where 100 by said bar is caused to project into the seat-space of the torch, means for engaging said bar and catch-lever on such projection of said bar, whereby on reseating said torch said catch-lever is released and said extinguisher 105 permitted to drop upon the torch-wick, substantially as set forth.

Signed by us this 21st day of January, 1899.

CHAS. B. ABBOTT.
SAMUEL ABBOTT.
